BOAT BOTTOM

George O. Huet, New Orleans, La., assignor to Higgins, Inc., New Orleans, La., a corporation of Louisiana
Filed Aug. 11, 1958, Ser. No. 754,308
12 Claims. (Cl. 114—56)

This invention relates in general to new and useful improvements in boat hull construction, and more specifically to a boat hull having an improved bottom construction.

In the design of a boat hull, the design of the bottom, particularly the bow portion of the bottom is very critical. In a high speed boat hull, it is highly desirable that the bow portion of the bottom be so designed whereby it will readily cut through the water so as to minimize resistance. On the other hand, it is necessary that the bow construction be of such a nature whereby the bow of the boat does not have the tendency to dive nor is it desirable that the bow is so constructed whereby the boat will continuously pound. Normally, in order to obtain an increase in speed, the bow is made relatively thin and thus valuable space is lost. Furthermore, when the bow is so constructed, there is little to resist the plunging of the bow with the result that the hull becomes unstable. On the other hand, if a relatively wide bow is used the frontal resistance is too great. Also, there is excessive pounding of the hull.

It is therefore the primary object of this invention to provide an improved boat hull construction wherein the bow is so constructed whereby maximum speed may be attained and at the same time resistance to the plunging of the bow is effected by forming the bow from a plurality of upwardly curving longitudinally extending chines.

Another object of this invention is to provide an improved boat hull construction wherein the bow of the hull is in the form of a plurality of longitudinally extending chines, the chines curving upwardly towards the bow whereby the forward movement of the boat hull results in the action of the water on the chines to lift the bow so that the desired trim of the boat is maintained, the chines having progressively more curvature higher up along the bottom and bow whereby the more the bow section is submerged, the greater the upper lifting force of the water on the bow.

Another object of this invention is to provide an improved boat hull construction wherein the bottom thereof generally after the center is of a smooth construction and may be flat, concave or convex, as desired, and the bow portion thereof is in the form of a plurality of longitudinally extending chines, the chines being so designed so as to effectively deflect the water downwardly with the forward motion of the hull whereby a much safer and drier boat results.

Another object of this invention is to provide an improved boat hull construction which is of such a nature whereby there is provided easy riding with a minimum of pounding, improved running trim and a resistance of a downward suction of the bow to give a positive lift, which increases the running trim and thereby assures a drier, safer boat.

A still further object of this invention is to provide a boat hull so shaped in construction, in the interest of increased speed, whereby the effective deflection of the bow wave at different zones is such to minimize the skin friction at all angles of longitudinal trim and wave conditions.

These together with other objects and advantages which will become subsequently apparent reside in the details of construction and operation as more fully hereinafter described and claimed, reference being had to the accom-

2

panying drawings forming a part hereof, wherein like numerals refer to like parts throughout, and in which:

FIGURE 1 is a side elevation of the boat hull embodying the features of the present invention;

FIGURE 2 is a bottom plan view of the boat hull of FIGURE 1;

FIGURE 3 is an enlarged transverse sectional view taken substantially upon the plane indicated by the section line 3—3 of FIGURE 1 and shows the transverse section of the boat hull in the vicinity of the stern;

FIGURE 4 is an enlarged transverse sectional view taken substantially upon the plane indicated by the section line 4—4 of FIGURE 1 and shows the transverse section of the boat hull just aft of the mid-point of the boat hull;

FIGURE 5 is an enlarged transverse sectional view taken substantially upon the plane indicated by the section line 5—5 of FIGURE 1 and shows the transverse section of the boat hull forwardly of the mid-point of the boat hull;

FIGURE 6 is an enlarged fragmentary sectional view taken substantially upon the plane indicated by the section line 6—6 and shows the transverse section of the boat hull and the rear part of the bow;

FIGURE 7 is an enlarged fragmentary sectional view taken substantially upon the plane indicated by the section line 7—7 of FIGURE 1 and shows the transverse section of the boat hull along the bow; and

FIGURE 8 is an enlarged fragmentary transverse sectional view showing the manner in which the chines are formed utilizing a metal construction.

Referring now to the drawings in detail, it will be seen that there is illustrated the boat hull which is the subject of this invention, the boat hull being referred to in general by the reference numeral 10. The boat hull 10, with the exception of the bow construction thereof, is conventional. The boat hull includes a pair of sides 12 and a bottom construction which is referred to in general by the reference numeral 14. The boat hull 10 also includes a bow 16 and a transom 18. The superstructure of the boat hull 10 has not been illustrated and may be varied as is desired.

As is best illustrated in FIGURE 2, the bottom 14 includes a rear portion 20 which is smooth and a forward portion 22 which is in the form of a plurality of longitudinally extending chines. The chines 24 extend entirely across the bottom.

Referring now to FIGURES 3 and 4 in particular, it will be seen that the rear portion 20 of the bottom 14 is of the V construction. However, for the purpose of this invention, it is only necessary that the rear portion 20 of the bottom 14 be smooth and if desired, it may be either V, concave, or convex.

At approximately the mid-point of the bottom 14, the smooth rear portion 20 is transformed into a plurality of longitudinally extending chines 24. The individual chines 24 extend entirely across the bottom 14 between the chines 26 at the intersections of the bottom 14 with the sides 12. The chines 24 curve upwardly toward the bow 16 as is best shown in FIGURE 1 and in the transverse sections of FIGURES 5, 6 and 7.

Referring now to FIGURE 8 in particular, it will be seen that the chines 24 are formed from the material used in constructing the bottom 14. Each chine 24 is formed by an offset edge portion or flange 28 of the bottom section 30. The offset edge portion 28 is secured to an adjacent longitudinal section 30 either by welding 32 or is formed integral therewith depending upon the particular hull construction. In any event, the width of the chines 24 is greatly in excess of the thickness of the material used in forming the bottom 14 and unlike the conventional lap strake construction, the chines 24 are formed for stabil-

ity purpose as opposed to being an inherent part of the construction. Because the width of the chines 24 is in no way dependent upon the thickness of the material used in the construction of the bottom 14, it will be seen that the bow construction of the hull 10 may have the desired qualities.

In the construction of the bottom 14, should the boat be relatively small and a light gauge metal is used, the chines 24 may be formed by a stamping or bending operation and the longitudinal sections 30 may be integral parts of a sheet. On the other hand, when the construction of the hull must be heavier duty because of the size of the hull, it is necessary that a particular gauge metal be used. This metal cannot be shaped so as to have the chines 24 formed from an integral construction. The individual sections 30 may either be cut from the sheet material used in forming the aft portion of the bottom 14 or may be separate strips. In the event separate strips are used, the individual strips 30 may be extruded.

In addition to the chines 24 and the normal chines 26 carrying at the intersection of the bottom and the sides of the boat hull, the forward portions of the sides 12 are provided with chines 34. The chines 34 terminate forwardly of the mid-point of the hull 10, as is best shown in FIGURES 1 and 2.

As will be readily apparent from the sections through the bow portion of the hull 10, there is an increase in deadrise over the normal deadrise. This increase in deadrise is obtained without the loss of sectional area which is highly desirable in a hull design.

Because of the shape of the chines and the maximum offset obtained with the present construction, it will be readily apparent that when the hull 10 has a tendency to nose down or plunge into the water, the surfaces of the offset striking the water will resist the downward plunging of the bow and give a positive lift thereto. Furthermore, because the individual chines 24 curve upwardly towards the bow, as the boat hull 10 moves forwardly, the reaction of the water on the chines 24 will give a positive lift which increases the running trim of the hull. This assures a drier and safer hull. On the other hand, because a maximum angle of deadrise is obtainable with the particular hull design, there is a minimum of pounding. The effective deflection of the bow wave in different zones due to the provision of the multiple chines along the bow at the bottom of the boat also minimizes skin friction at all angles of longitudinal trim and wave conditions and thus results in increased speed, thus the provision of the multiple annular chines dividing the hull bottom and sides into different zones results in a faster boat which has less pounding and safer riding qualities without sacrificing sectional area in the bow.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. In a boat hull, a bottom construction, said bottom construction comprising a smooth after portion and a ribbed forward portion said forward and aft portions being continuous and defining a longitudinally extending continuous planing surface, said ribbed forward portion being in the form of a plurality of angular chines defining longitudinally extending strip like areas with said areas being joined by outwardly and downwardly facing longitudinally extending flanges whereby an increased angle of deadrise is possible without loss of sectional area, said strip like areas terminating at their rear ends in end portions substantially paralleling the longitudinal center line of said hull.

2. In a boat hull, a bottom construction, said bottom

construction comprising a smooth after portion and a ribbed forward portion said forward and aft portions being continuous and defining a longitudinally extending continuous planing surface, said ribbed forward portion being in the form of a plurality of angular chines defining longitudinally extending strip like areas with said areas being joined by outwardly and downwardly facing longitudinally extending flanges whereby an increased angle of deadrise is possible without loss of sectional area, said strip like areas terminating at their rear ends in end portions substantially paralleling the longitudinal center line of said hull, each of said flanges being integral with the next adjacent area toward the longitudinal center line of the hull.

3. In a boat hull, a bottom construction, said bottom construction comprising a smooth after portion and a ribbed forward portion said forward and aft portions being continuous and defining a longitudinally extending continuous planing surface, said ribbed forward portion being in the form of a plurality of angular chines defining longitudinally extending strip like areas with said areas being joined by outwardly and downwardly facing longitudinally extending flanges whereby an increased angle of deadrise is possible without loss of sectional area, said strip like areas terminating at their rear ends in end portions substantially paralleling the longitudinal center line of said hull, the exposed width of each of said flanges being greater than the thickness of the material from which said chines are formed.

4. In a boat hull, a bottom construction, said bottom construction comprising a smooth after portion and a ribbed forward portion said forward and aft portions being continuous and defining a longitudinally extending continuous planing surface, said ribbed forward portion being in the form of a plurality of angular chines defining longitudinally extending strip like areas with said areas being joined by outwardly and downwardly facing longitudinally extending flanges whereby an increased angle of deadrise is possible without loss of sectional area, said strip like areas terminating at their rear ends in end portions substantially paralleling the longitudinal center line of said hull, each of said flanges being integral with the next adjacent area toward the longitudinal center line of the hull, the exposed width of each of said flanges being greater than the thickness of the material from which said chines are formed.

5. In a boat hull, a bottom construction, said bottom construction comprising a smooth after portion and a ribbed forward portion said forward and aft portions being continuous and defining a longitudinally extending continuous planing surface, said ribbed forward portion being in the form of a plurality of angular chines defining longitudinally extending strip like areas with said areas being joined by outwardly and downwardly facing longitudinally extending flanges whereby an increased angle of deadrise is possible without loss of sectional area, said strip like areas terminating at their rear ends in end portions substantially paralleling the longitudinal center line of said hull, said boat hull having sides, said chines extending completely between said sides.

6. In a boat hull, a bottom construction, said bottom construction comprising a smooth after portion and a ribbed forward portion said forward and aft portions being continuous and defining a longitudinally extending continuous planing surface, said ribbed forward portion being in the form of a plurality of angular chines defining longitudinally extending strip like areas with said areas being joined by outwardly and downwardly facing longitudinally extending flanges whereby an increased angle of deadrise is possible without loss of sectional area, said strip like areas terminating at their rear ends in end portions substantially paralleling the longitudinal center line of said hull, said boat hull having sides, said chines extending completely between said sides, said sides including forward portions, a lower part of each side forward por-

tion being in the form of an angular chine corresponding to said chines of said bottom construction.

7. In a boat hull, a bottom construction, said bottom construction comprising a smooth after portion and a ribbed forward portion said forward and aft portions being continuous and defining a longitudinally extending continuous planing surface, said ribbed forward portion being in the form of a plurality of angular chines defining longitudinally extending strip like areas with said areas being joined by outwardly and downwardly facing longitudinally extending flanges whereby an increased angle of deadrise is possible without loss of sectional area, said strip like areas terminating at their rear ends in end portions substantially paralleling the longitudinal center line of said hull, each of said flanges being integral with the next adjacent area toward the longitudinal center line of the hull, said boat hull having sides, said chines extending completely between said sides.

8. In a boat hull, a bottom construction, said bottom construction comprising a smooth after portion and a ribbed forward portion said forward and aft portions being continuous and defining a longitudinally extending continuous planing surface, said ribbed forward portion being in the form of a plurality of angular chines defining longitudinally extending strip like areas with said areas being joined by outwardly and downwardly facing longitudinally extending flanges whereby an increased angle of deadrise is possible without loss of sectional area, said strip like areas terminating at their rear ends in end portions substantially paralleling the longitudinal center line of said hull, the exposed width of each of said flanges being greater than the thickness of the material from which said chines are formed, said boat hull having sides, said chines extending completely between said sides.

9. In a boat hull, a bottom construction, said bottom construction comprising a smooth after portion and a ribbed forward portion said forward and aft portions being continuous and defining a longitudinally extending continuous planing surface, said ribbed forward portion being in the form of a plurality of angular chines defining longitudinally extending strip like areas with said areas being joined by outwardly and downwardly facing longitudinally extending flanges whereby an increased angle of deadrise is possible without loss of sectional area, said strip like areas terminating at their rear ends in end portions substantially paralleling the longitudinal center line

35 40 45

of said hull, said boat hull having sides, said chines extending completely between said sides, said sides including forward portions, a lower part of each side forward portion being in the form of an angular chine corresponding to said chines of said bottom construction, the exposed width of each of said flanges being greater than the thickness of the material from which said chines are formed.

10. In a boat hull, a boat bottom construction, said bottom construction comprising a smooth after portion and a ribbed forward portion, said forward and aft portions being continuous and defining a longitudinally extending continuous planing surface, said ribbed forward portion being in the form of a plurality of angular chines spaced transversely of and extending longitudinally of said forward portion between opposite sides thereof, said angular chines including at least rear end portions substantially paralleling the longitudinal center line of said hull.

11. The combination of claim 10 wherein said forward portion terminates at its forward end in a bow structure, said angular chines on opposite sides of a vertical plane containing the longitudinal center line of said hull curving upwardly toward said bow and being forwardly convergent.

12. The combination of claim 10 wherein said hull has sides, said chines extending completely between said sides, said sides each being provided with at least one longitudinally extending chine in the forward portion of said hull spaced slightly above the bottom edges thereof, said side chines curving upwardly toward the bow of said hull.
